STEAM IRON

Edmond G. Franklin and Stanton W. Holmberg, Minneapolis, Minn., assignors to General Mills, Inc., a corporation of Delaware

Application March 12, 1954, Serial No. 415,812

10 Claims. (Cl. 38—77)

This invention relates to steam irons and pertains more particularly to an iron capable of performing either steam or dry ironing operations.

In steam irons equipped with boilers of limited volume the liquid entering the boiler is permitted to seek the level of that contained in the reservoir merely by providing an unmetered valve arrangement. Stated otherwise, the valve is either "on" or "off" and the quantity of steam fed to the ironing face of the soleplate is governed by the amount of heat supplied to the boiler from the soleplate. In such situations the boiler is preferably located near the front end of the iron so as to take advantage of the concentrated heat zone due to the conventional convergence of the embedded heating element in this forward region. Through inadvertence, and in actually performing some pressing operations, the toe or forward end of the iron may be tilted downwardly, which in the above alluded-to type of steam iron carries with it the attendant disadvantage of having the liquid level in the boiler rise to such a height that water is carried with the steam from the boiler to the pressing face of the iron.

Accordingly, it is one important object of the invention to obviate the likelihood of the water level in the boiler rising to such an extent that water will be carried with the steam onto the fabric being ironed.

Another object of the invention is to provide conduit means for carrying out the foregoing object and also permitting the resting of the iron on either of its sides with an automatic shutting off of the liquid flowing to the boiler.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings, Figure 1 is an elevational view in section taken in the direction of line 1—1 of Fig. 2;

Fig. 2 is a horizontal sectional view taken in the direction of line 2—2 of Fig. 1, and

Fig. 3 is a perspective view of the iron, partly in section, to show the internal arrangement of the conduit means permitting the tilting of the iron.

Referring to the drawings in detail, the iron selected for the purpose of illustrating the invention includes a soleplate 10 having embedded therein a conventional U-shaped heating element 12. The heating element 12 is energized by way of an electrical cord adapted to be connected to a source of power and containing a pair of conductor elements 16 and 18. The element 16 is connected directly to one end of the heating element 12 and the other element 18 completes the circuit through the heating element but includes therein a thermostatic switch 20. The thermostatic switch 20 is adjustable by reason of an upstanding shaft 22 provided at its upper extremity with a manipulating knob 24. Thus, once the thermostatic switch 20 has been adjusted for a particular

2

temperature this switch will control the energization of the heating element 12 and consequently the amount of heat supplied to the soleplate.

Surmounting the soleplate 10 is a reservoir 26 retained in fixed relationship with the soleplate by virtue of such mounting means as studs 28 and nuts 30. Reservoir 26 includes a substantially flat bottom 32 and in the illustrated embodiment there is an outlet provided at 34. Liquid contained within the reservoir is fed to the outlet via a rearwardly extending tubular member 36. As shown, the tubular member 36 is semi-circular when viewed in cross section and includes laterally extending flanges 38 which may be soldered or brazed to the bottom 32. In this way an intake to the presently to be described steam generating chamber is formed at 40 near the rear end of the reservoir.

In order to generate steam which is to be supplied to the pressing face of the soleplate, the iron includes an upstanding steam generating chamber in the form of a cylindrical boiler 42 having its lower end abutting an annular gasket 44. Within the boiler 42 is centrally disposed a steam delivery tube 46, the tube 46 having communication with the interior of the boiler by reason of an aperture 48. The lower end of the tube is threaded at 49 and is threadedly received in an aperture 50 extending through the soleplate 10. Preferably a series of grooves 51 connecting with the lower end of the aperture are desired for better steam distribution during an ironing operation. Carried at the upper end of the steam delivery tube 46 is a stud member 52, which stud member extends through the dome-shaped top of the boiler 42, there being an aperture 54 through which the stud passes. A gasket 56 and a nut 58 threadedly engaged with the upper end of the stud 52 assure a vapor-tight seal at the upper end of the boiler.

In order to provide communication between the outlet 34 and the lower portion of the boiler a radially and then upwardly directed tubular passage 60 is provided. Also circumscribing the outlet 34 is a bushing 62 which contains therein a valve member 64. The valve member 64 is designed to seat against the bottom 32 of the reservoir so as to either permit or prevent flow of liquid to the boiler by way of the passage means 60. For the purpose of actuating the valve member 64, such member is equipped with a vertically extending stem 66 having encircled thereabout a compression spring 68. The compression spring 68 is instrumental in normally holding the valve in a closed position. Threadedly engaged with the upper end of the bushing 62 is a threaded member 70 having a bore 72 extending therethrough.

Not only does the bore 72 accommodate the stem 70 but is also of sufficient size to permit the venting of the reservoir. In this connection bushing 62 has an opening 74 adjacent its upper end and the member 70 has a similar opening 76 leading to atmosphere. In this way the venting takes place through the openings 74 and 76 and the bore 72. Mounted on the upper end of the valve stem 66 is a knob 78 having a downwardly extending projection 80. The projection 80, when the valve is closed, is spaced radially outward from the top of the member 70. However, to open the valve the knob 78 may be rotated to an extent sufficient to bring the projection 80 in a superimposed relation with a radially extending ear 82 which is integral with the member 70. Thus the projection 80 will be maintained at a raised elevation and the valve member 64 will accordingly be moved into an open position with respect to the outlet 34.

To limit the filling of the reservoir 26 to only a certain extent it is contemplated that the top thereof be recessed in the region indicated by the numeral 84. The recessed portion 84 is apertured at its lower end as indicated by the numeral 86 and this aperture is threaded for the recep-

tion of a water-tight fill plug 88. To assure a water-tight seal, a gasket 90 is disposed beneath the enlarged upper end of the fill plug, and to permit facile removal of the plug, the plug may be provided with a finger-engaging portion 92. By virtue of the recessed disposition of the filler plug, it will be observed that in filling or replenishing the reservoir with liquid the level of the liquid will only rise to the elevation designated by the numeral 94. The reason for such a limited filling of the reservoir will be made manifest in the operational description of the iron.

Also included as part of the iron is a handle 96, the handle being secured to the reservoir by means of fastening elements such as screws 97. Further, the iron includes a pair of projections 98, one attached to each side of the iron. These projections 98 function as feet for supporting the iron in a side-rest position. As will be discerned from Fig. 3, the feet 98 are disposed so that the forward end or toe of the iron will be maintained at a higher elevation than the rear of the iron when the iron is placed on either of its sides.

While the operation of the iron is thought to be apparent from the foregoing description, nonetheless, a brief operational sequence will be given at this time. The iron is filled by removing the fill plug 88 and holding the iron in a substantially horizontal position. When the iron has been filled to its upper limit as indicated by the numeral 94, the iron is ready for use. Assuming that a steam ironing operation is to be performed, the thermostat 20 is adjusted for the proper operating temperature by means of the knob 24 and the valve 64 is moved into open position by manipulation of the knob 78.

Opening of the valve permits water to flow gravitationally to the lower end of the boiler 42 via the inlet 40, the tube 36, the outlet 34, and the tubular passage 60. The water entering the boiler 42 will immediately rise to the same height as the water contained in the reservoir since it is contemplated that the valve arrangement be of the unmetered variety, i. e., either fully opened or closed.

Due to the proximal relation of the lower end of the boiler 42 with the soleplate 10, heat is conducted to the region embraced by the boiler from the heating element 12. This heat is fairly concentrated in this particular zone due to the fact that the heating element is substantially of U-shaped configuration, the sides of the heating element coming to fairly close subjacency to said boiler.

Steam generated within the boiler passes upwardly and is directed through the opening 48 to the steam delivery tube 46. Having entered the tube 46, the steam then proceeds downwardly through the aperture 50 to the ironing face of the soleplate.

Now, if the toe of the iron is tilted downwardly it will be observed that the water level in the boiler begins to go up as the water tries to reach the level of that in the elevated rear end of the reservoir. Such a condition, if allowed to continue, would be responsible for carrying actual water into the steam delivery tube 46. This is not necessarily due to having the water level reach the aperture 48 but the increased amount of water entering the boiler, together with the turbulence from boiling, causes the steam to carry drops of water over into said delivery tube 46. It is to avoid the foregoing happening that the tube 36 is incorporated into the iron, for the entrance 40 of the tube is disposed sufficiently rearwardly so as to bring this entrance out of the water contained in the reservoir before an objectionable amount of water has entered the boiler 42. In this way, the user of the iron will not experience staining or discolorization from water contact which would otherwise occur in connection with certain fabrics.

Also it will be noted that the height of the vent opening 76 is at such an elevation that when the iron is tilted with its toe downward, the water in the reservoir will not flow out through the opening 76. Thus it will be seen that the reservoir is properly vented and that the venting

arrangement does not permit the inadvertent escape of water therethrough.

Not only is it within the purview of the invention to prevent the level of the water within the boiler 42 from rising unduly, but the invention also contemplates a tubular arrangement that will permit the iron to be side-rested on either of its sides with a concomitant shut-off of water being fed to the boiler 42. In this connection it is to be observed that the outlet 34 is positioned in fairly close proximity to the front end of the iron and that this outlet is raised above the level of the water when the iron is in the position pictured in Fig. 3. Consequently the means providing communication from the interior of the reservoir to the interior of the boiler extends forwardly as evidenced by the tubular portion 36 and then rearwardly as evidenced by the tubular portion bearing the numeral 60. In order to permit the iron to be rested on either of its sides, the outlet 34 is located substantially on the longitudinal center-line of the reservoir and will be above the water level whether the iron is in its side-rested position shown in Fig. 3 or is positioned on its opposite side.

As many changes could be made in the above construction and many apparently widely different embodiments of the invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

We claim:

1. In a steam iron, a soleplate, a reservoir surmounting the soleplate, a steam generating chamber associated with the soleplate, and passage means adjacent the bottom of the reservoir between said reservoir and said steam generating chamber extending forwardly from a locus near the rear of the reservoir to a locus near the front of said reservoir and then rearwardly to said chamber for gravitationally feeding liquid from said reservoir to said steam generating chamber.
2. The structure set forth in claim 1 including means for supporting the iron in a side rest position and downwardly recessed means in the top of the reservoir for limiting the filling of the reservoir so that said forward locus will be above the level of the reservoir's contents when the iron is in its side rest position.
3. The structure set forth in claim 2 including a tubular vent issuing upwardly from the top side of said reservoir near the forward end thereof for venting the interior of the reservoir to atmosphere and said means for limiting the filling of the reservoir is disposed substantially on the transverse center line of the iron and includes a liquid tight fill plug.
4. In a steam iron, a soleplate, a reservoir surmounting the soleplate provided with an aperture in its bottom side near the front end of the iron, a steam generating chamber associated with the soleplate and disposed toward the front end of the iron but rearwardly of said aperture, a tube having communication with said aperture extending rearwardly along the upper surface of said bottom side to provide an inlet near the rear end of said reservoir, and conduit means beneath said reservoir establishing communication between said aperture and said steam generating chamber to feed liquid gravitationally from the reservoir via said tube, aperture and conduit means only when said inlet is beneath the liquid contained in said reservoir.
5. The structure set forth in claim 4 including a valve for opening and closing said aperture.
6. In a steam iron, a soleplate, an electrical heating element in heat transfer relation with the soleplate, a reservoir surmounting the soleplate, a steam generating cham-

ber disposed intermediate the ends of said soleplate, passage means connecting said reservoir with said steam generating chamber, said passage means extending first forwardly from a locus near the rear of said reservoir to a locus substantially on the longitudinal center line of the iron near the front thereof and then rearwardly to said steam generating chamber at an elevation adjacent the bottom of said reservoir, a side rest projection at each side of the iron located so as to maintain the forward end of the iron at an elevation above the rear end of the iron when said iron is resting on either side, and means limiting the complete filling of the reservoir so that said forward locus is above the level of the reservoir's contents when the iron is in either side rest position.

7. In a steam iron, a soleplate including steam discharge means leading to its pressing face, electrical heating means embedded in the soleplate having a U-shaped configuration, a reservoir surmounting the soleplate, a boiler including an upstanding hollow shell on said soleplate and forming a steam generating chamber with the soleplate of limited volume, said boiler being nearer the forward end of the iron than the rear, means for gravitationally conducting liquid from the reservoir to the boiler including a tube extending from a point near the rear end of the reservoir along the bottom thereof to said boiler, and a steam delivery tube connecting the boiler with said discharge means.

8. In a steam iron, a soleplate including steam discharge means leading to its pressing face, electrical heating means embedded in the soleplate having a U-shaped configuration, a reservoir surmounting the soleplate, a boiler including an upstanding cylindrical shell on said soleplate and forming a steam generating chamber with the soleplate of limited volume, said boiler being dis-

posed adjacent the bight of said U-shaped heating means, means for conducting liquid from the reservoir to the boiler including a conduit portion extending from a point near the rear end of the reservoir around one side of the boiler to a point in front of the boiler and a conduit portion extending from said last named point rearwardly to said boiler, and a steam delivery tube within said cylindrical shell connecting the boiler with said discharge means.

9. The structure set forth in claim 8 including a valve between said conduit portions.

10. The structure set forth in claim 9 in which said last named point is located substantially on the longitudinal center line of the iron and the structure further includes a side rest projection at each side of the iron located so as to maintain said last named point above the rear end of the iron when said iron is resting on either side, and means limiting the filling of the reservoir so that said last named point is above the level of the reservoir's contents when the iron is in either side rest position.
